Marshall F. Thompson, 3112 W. Marshall St.,
Richmond, Va. 23200

Filed Apr. 15, 1969, Ser. No. 16,748

Term of patent 14 years

Int. Cl. D14—02

U.S. Cl. D26—14

FIG. 1 is a perspective view showing the top, front and one side of the combined free standing table top voting switch and microphone support, showing my new design;

FIG. 2 is a front elevational view thereof;

FIG. 3 is a top plan view thereof; and

FIG. 4 is a side elevational view showing the side opposite that shown in FIG. 1, the back and bottom being substantially plain.

The broken lines are shown for illustrative purposes only, and form no part of the claimed design.

I claim:

The ornamental design for a combined free standing table top voting switch and microphone support, substantially as shown and described.
